UNITED STATES PATENT OFFICE.

BENJAMIN E. D. STAFFORD, OF PITTSBURGH, PENNSYLVANIA, ASSIGNOR TO
FLANNERY BOLT COMPANY, OF PITTSBURGH, PENNSYLVANIA.

FLEXIBLE STAY-BOLT.

1,119,653.

Specification of Letters Patent.

Patented Dec. 1, 1914.

Application filed April 1, 1914. Serial No. 828,866.

To all whom it may concern:

Be it known that I, BENJAMIN E. D. STAFFORD, of Pittsburgh, in the county of Allegheny and State of Pennsylvania, have 5 invented certain new and useful Improvements in Flexible Stay-Bolts; and I do hereby declare the following to be a full, clear, and exact description of the invention, such as will enable others skilled in 10 the art to which it appertains to make and use the same.

My invention relates to an improvement in flexible stay bolts.

The inspection of stay bolts within fixed 15 periods, is mandatory, and to inspect and test them the heads of the bolts must be exposed for tapping and turning.

With stay bolts now in use, the head of the bolt is mounted in a sleeve and is covered by a cap secured to the sleeve. The 20 pressure of the head of the bolt against the inside of the sleeve tends to bulge or expand the latter, thus causing the cap to stick. Again the formation of rust on the threads 25 connecting the cap and sleeve retards removal of the cap, hence it is usually necessary to loosen the cap by striking it with a hammer which frequently results in fracture or injury to the cap or sleeve. Again 30 when the cap is stuck fast, the efforts to unscrew it result at times in loosening up the connection between the sleeve and the outer sheet of the boiler.

The object of the present invention is to 35 provide for the quick and ready inspection of the stay bolt proper without danger of injury to the parts in which the head of the bolt is mounted, and it consists in the parts and combinations of parts as will be more 40 fully explained and pointed out in the claims.

In the accompanying drawings, Figure 1 is a view in side elevation, partly in section 45 of my improvement and Fig. 2 is a view in plan of the same.

1 represents the bolt preferably provided with a substantially spherical head 2, having a slot 3 for the engagement of a suitable driver.

50 Secured to the outer sheet 4 of the boiler is the sleeve 5, threaded externally. This sleeve which is preferably drop forged or a malleable casting, has a bore or opening at its inner end of greater diameter than the 55 body of the bolt 1, and is made flaring so

as to permit of a free lateral or rocking movement of the bolt within reasonable limits. This sleeve is designed to receive and house the head 2 of the bolt, and is provided internally with a seat 6, formed in the arc of a circle concentric with the head 2 of the bolt, against which said head rests, and which permits of a universal movement of the head on its seat during the movements caused by expansion and contraction of the sheets to which the bolt is connected. The bore or cavity in the sleeve 5, above or to the outerside of the seat 6, is of a size sufficient for the free entrance of the head of the bolt, and the sleeve 70 is preferably provided externally adjacent its outer end with the hexagonal or otherwise angular portion 7 for the wrench employed for attaching the sleeve to the boiler sheet. The sleeve 5 is provided at its outer 75 end with two pairs of outwardly projecting perforated ears 8, the ears of each pair being spaced apart so as to receive between them the lugs 9 cast integral with the ring 10, the lugs being also perforated so that 80 when the parts are assembled the ring 10 will be held against the outer end of the sleeve by tool steel pins 14 passing through the holes in the ears 8 and lugs 9.

The ring 10 is threaded internally for the 85 attachment of the plug 11, the inner end of which is preferably concaved and provided with rounded edges or periphery as shown, which latter is covered by a spun brass or copper gasket 12 secured to the 90 inner end of the plug 11, by bending it up and around the rounded edge of the plug, thus forming curved bearing edge which, when the parts are assembled bears against the annular inclined seat 13 formed at the 95 outer edge of the sleeve just within the outer end of the latter. The plug 11 is provided in its outer face with an angular recess or holes for the attachment of a suitable tool for rotating it in the ring.

When the parts are assembled in operative 100 position, the ring and its plug are locked against the end of the sleeve as shown in full lines in Fig. 1. To expose the head for inspection of the bolt, the plug is turned in 105 a direction to ease up the pressure of its rear end against the seat 13, thus withdrawing the pressure on the pins 14 after which one of the pins may be removed thus leaving the ring 10 and plug 11 carried thereby, free to 110

be turned out of the path of the sleeve, as shown in dotted lines in Fig. 1. After the bolt has been tested, the parts may be again locked by turning the ring down and 5 securing it to the sleeve by the pin, and then by screwing in the plug the parts will be locked and the bolt head housing sealed. When necessary or desirable, the ring 10 may be disconnected from the sleeve by 10 simply removing both pins 14, or the upper portion of the sleeve carrying the ring may be separate from the sleeve and screwed thereto, as illustrated by the dotted threads shown in Fig. 1.

15 I would have it understood that the particular means shown for securing the ring to the sleeve are unimportant, hence I would have it understood that I do not confine myself to the details shown except as required 20 by the scope of the claims.

Having fully described my invention what I claim as new and desire to secure by Letters-Patent, is:—

25 1. In a flexible stay bolt construction, the combination of a sleeve adapted for attachment to a boiler sheet and having a seat for a stay bolt head, a member adapted for removable attachment to the sleeve and a movable plug carried by said member and adapted 30 to make contact with a shoulder in the sleeve.

35 2. In flexible stay bolt construction, the combination of a sleeve adapted for attachment to a boiler sheet and having a seat for a stay bolt head, a ring hinged to the sleeve and a movable plug carried by said ring and adapted to close the outer end of the sleeve.

40 3. In a flexible stay bolt construction, the combination of a sleeve adapted for attachment to a boiler sheet and having a seat for

a stay bolt head and a seat for an end closure, a ring removably attached to said sleeve and a screw plug carried by said ring and adapted to bear against said shoulder and form the outer end closure for the sleeve. 45

4. In flexible stay bolt construction, the combination of a sleeve adapted for attachment to a boiler sheet and having a seat for a stay bolt head, a ring having hinged connection with the end of the sleeve and a screw plug carried by the ring and adapted to close the outer end of the sleeve. 50

5. In flexible stay bolt construction, the combination of a sleeve having a seat, and a screw plug having a soft metal facing permanently secured thereto for contact with said seat on the sleeve for closing the outer end of same. 55

6. In flexible stay bolt construction, the combination of a sleeve having an inclined seat, a ring movably secured to the outer end of the sleeve and a screw plug carried by said ring and provided with a soft metal facing adapted to make contact with the inclined seat in the sleeve. 60

65 7. In a flexible stay bolt construction, the combination of a sleeve adapted for attachment to a boiler sheet, and having a seat for a stay bolt head, a member movably attached to the outer end of the sleeve and a plug carried by said movable member and adapted to form the outer closure of the sleeve. 70

75 In testimony whereof, I have signed this specification in the presence of two subscribing witnesses.

BENJAMIN E. D. STAFFORD.
